UNITED STATES PATENT OFFICE.

ABRAHAM ASHKENAS, OF BROOKLYN, NEW YORK.

SCREEN.

Application filed December 9, 1927. Serial No. 238,806.

This invention relates to screens and the improvements are directed to novel and unique means for providing decorative effects of wide and varying scope.

5 The primary object of the invention resides in the provision of certain panel-supporting means, in the form of standards, wherein panels in the nature of decorative posters may be removably applied thereto.

10 Another object is to provide said standards with a plurality of grooves, disposed at varying angles, whereby a series of panels may be applied and arranged in different angular positions.

15 Still another object of the invention resides in the provision of standards wherein the grooves extend to a point adjacent the base thereof to permit the placement of a panel having its bottom edge in close proximity to 20 a floor or the like.

Still another object is to provide standards wherein the grooves terminate short of the base thereof to permit the use of panels having their bottom edges spaced an appreciable 25 distance from the floor.

20 A still further object of the invention is to provide means for locking said panels within the selected grooves in said standards, said locking means preferably being associated 30 with frames which may be attached to the standards at any point within the grooves thereof to permit the use of panels of varying widths.

35 A further object is to provide each of said standards with a plurality of radially extending grooves tapering toward the centers of said standards and permitting of a force-fit by engagement with the lateral extremities of said panels.

40 Another object is to provide a structure which may be readily assembled and taken apart to permit its packing for shipment in a compact package.

45 With these objects in view, together with others which will appear as the description proceeds, the invention resides in the novel formation, combination, and arrangement of parts, all as will be described more fully hereinafter, illustrated in the drawings, and particularly pointed out in the claims.

In said drawings:

Figure 1 is an elevation of my improved screen, illustrating a pair of standards, or uprights, mutually supporting a panel, the

grooves provided in said standards terminating short of the base of the same to position the panel an appreciable distance above a floor, or the like.

55 Fig. 2 is an enlarged sectional view taken on the plane of the line 2—2 of Fig. 1, to illustrate the radial grooves having tapered sides.

60 Fig. 3 is an enlarged elevation of the upper portion of a standard, partly in section, to illustrate the locking means associated with certain frames, said locking means being 65 shown just prior to its attachment to said standard.

70 Fig. 4 is an enlarged sectional view on the line 4—4 of Fig. 1, showing the locking means attached to said standard.

75 Fig. 5 is an enlarged section on the line 5—5 of Fig. 1 to depict the clasping action of certain frames with respect to the panels.

Fig. 6 is an elevation of a modified form of standards wherein the grooves extend substantially to the base thereof to permit the use of a panel having its bottom edge in close proximity to a floor.

80 Fig. 7 is an enlarged section on the line 7—7 of Fig. 6 illustrating grooves having straight sides.

85 Fig. 8 diagrammatically illustrates the use of a plurality of standards wherein the panels positioned therebetween may assume varying angular positions in the furtherance of decorative effects; and

Fig. 9 is a view like unto Fig. 8, but showing another arrangement.

Referring now in detail to the accompanying drawings, wherein like characters of reference denote similar parts throughout the several views, let 10 denote the standard depicted in Fig. 1, which comprises a decorated base portion of suitable configuration, as indicated at 11, and which is provided with a terminal portion 12 conforming to the general scheme of decoration, each standard or upright 10 having a suitable base portion 13 to firmly support the structure. As clearly shown in Figs. 1 and 2, a portion of the longitudinal dimension of said standards is provided with a series of grooves 14, disposed radially thereof and terminating flush with the flat surface of the standard shown as octagonal in cross-section in this particular instance.

90 The sides of the grooves 14 taper inwardly and are adapted to engage the lateral extremities of the panels 15 for maintaining

95

100

105

the same in assembled relation, yet permitting of easy disassembling when the structure is to be shipped.

In assembling the structure the panels may be inserted in selected grooves and built up to embody a plurality of panels arranged at different angles, if desired, with respect to each other, as shown in Figs. 8 and 9. While Fig. 1 illustrates but a pair of standards and a single panel, it is, of course, to be understood that the continuance of the standards and panels therebetween is only limited by the particular use and conditions surrounding the same.

15 When a panel is used having a width substantially conforming to the length of the grooves 14, the bottom edge thereof will abut the top of portion 11 and receive support therefrom. However, it is frequently desirable to use a panel of short width and in this instance I provide frame members 16 and 17 positioned respectively at the top and bottom of said panels. Each of said frames is substantially U-shaped in cross-section, having 25 resilient leg portions, as indicated at 19, for clasping the longitudinal edges of said panels, extremities of said frames being provided with a bearing portion 20, (Fig. 3), to rotatably receive a locking device 21 having a 30 sharpened prong 22 at one end and adapted for forceful insertion in the side of one of the grooves upon manipulation of the operating portion 23 extending outside of said frames.

35 As shown in Fig. 1, the shorter panel used therein has its bottom edge engaged by the frame 17 and upon manipulation of the locking means the same is held in spaced relation above the bottom terminal of said grooves. 40 While said frames are primarily for the purpose of supporting and locking the panels in position, the particular use of the locking means finds adaptation when panels of short widths are used. However, the use of the 45 frames add to the artistic arrangement of the structure in that they blend with the standards to complete a border-effect.

In the form of standard shown in Fig. 6 the grooves extend from the top thereof to 50 the base portion 13 and in this arrangement the bottom edge of the panel 15 is in close proximity to the floor and obviously affords protection from drafts in the event the screen is used adjacent beds or other points in a room being ventilated. The bottom frame 55 17 may be used also in this instance and the locking means associated therewith brought into action in the event a short width panel is used.

60 While the preferred form of groove 14 is shown as tapered in Fig. 2, I may also pro-

vide some of the standards with straight-sided grooves 24 as shown in Fig. 7; otherwise they resemble the preferred form.

In actual practice the panels 15 will be provided with decorative effects involving scenery or the like and in view of the idea of changing the angularity thereof pleasing effects may be secured for advertising and window display work. When the panels are to be removed for shipping or other purposes the locking means is operated to disengage the prong from the position shown in Fig. 4, whereupon the frames and panels may be readily removed, it being understood that in some instances the locking means may be eliminated.

While the present is a disclosure of the preferred embodiments of the invention, it is to be understood that the invention is not limited thereto, as various changes in the minor details of construction, proportion and arrangement of parts may be resorted to liberally without departing from the spirit of the invention as defined in the appended claims.

I claim:

1. In a screen, a plurality of standards having a series of tapered grooves disposed radially of said standard and extending partially longitudinally thereof, panels positioned between said standards and having their lateral extremities inserted in selected grooves, frames adapted to clasp a longitudinal edge of said panels and means rotatably borne by said frames for locking said panels to said standards.

2. In a screen, a plurality of standards each presenting a series of radial grooves, each having their side walls converging toward the vertical axis of each of said standards and extending longitudinally thereof and terminating short of the base, panels positioned between said standards and having their lateral extremities inserted in selected grooves, frames adapted to clasp the top and bottom longitudinal edges of said panels and means rotatably borne by said frames for locking said panels to said standards.

3. In a screen, a plurality of standards each presenting a series of radial grooves extending longitudinally thereof and terminating short of the base, panels positioned between said standards and adapted for insertion in said grooves at varying angular positions, frames adapted to clasp the longitudinal edges of said panels and means rotatably borne by said frames for locking said panels to said standards, said means including prongs adapted to be inserted in the walls of said grooves.

In witness whereof I affix my signature.

ABRAHAM ASHKENAS.
